UNITED STATES PATENT OFFICE.

JOHN G. L. BOETTCHER, OF BROOKLYN, NEW YORK.

DESIGN FOR FAUCET-HANDLE.

Specification forming part of Design No. 7,452, dated May 26, 1874; application filed May 14, 1874.
[Term of Patent 14 years.]

To all whom it may concern:

Be it known that I, JOHN G. L. BOETTCHER, of Brooklyn, county of Kings and State of New York, have invented a new and original Design for Faucet-Handle; and I do hereby declare the following to be a full, clear, and exact description thereof, which will enable those skilled in the art to make and use the same, reference being had to the accompanying drawing forming part of this specification, which drawing represents a side elevation of a faucet with my handle.

My design consists in the combination of a roll bent in the form of a semicircle with a base which extends from the plug of the faucet. The ends of the base and the middle portion of the semicircular roll are ornamented by buttons with pointed heads.

In the drawing, the letter A designates a faucet, on the plug B of which is secured a base, C, that forms the support for the finger-piece D. This finger-piece is composed of a roll bent in the form of a semicircle, so that its ends bear flat on the base C. With the base C and the semicircular roll D are combined buttons *a a b*, the buttons *a a* being at-

tached to the under surface of the base C, near its ends, and the button *b* being secured in the middle of the semicircular roll D. These buttons serve as ornaments for the handle. A button, *c*, of similar shape, is placed on the end of the plug B.

By combining the semicircular roll D with the base C, a faucet-handle of a novel and distinguishing appearance is produced, and the ornamental appearance of this handle is further improved by the buttons *a a b*.

What I claim as new, and desire to secure by Letters Patent, is—

1. The design for a faucet-handle composed of a base, C, and a semicircular roll, D, as shown and described.

2. The design for a faucet-handle composed of a base, C, a semicircular roll, D, and buttons *a a b*, as shown and described.

This specification signed by me this 9th day of May, 1874.

JOHN G. L. BOETTCHER.
